Henry Williams

UNITED STATES PATENT OFFICE.

WILLIAM P. BIGELOW, OF NATICK, MASSACHUSETTS.

DESIGN FOR A MUSIC-STAND.

Specification forming part of Design No. 6,538, dated April 1, 1873; application filed February 17, 1873.

To all whom it may concern:

Be it known that I, WILLIAM P. BIGELOW, of Natick, in the county of Middlesex and State of Massachusetts, have invented a Design for Paper and Music Racks, of which the following is a specification:

The nature of my design is fully represented in the accompanying drawing, to which reference is made.

Figure 1 is a view in perspective of a paper-rack embodying my design. Fig. 2 is a vertical section of the same.

a represents the standard, which spreads into feet *a'* and supports the rack. *b* is the upper end of the standard and forms a convenient handle. *c c* are pockets intended to hold

papers, &c. *c' c'* are flexible sides to the pockets *c c*. *c'' c''* are oval openings in the pockets *c c*, intended to hold pictures or to be filled in in any tasteful manner.

The paper-rack herein represented forms a handsome and tasty article of furniture.

Having thus fully described my invention, what I claim, and desire to secure by Letters Patent, is—

The design for a rack or stand for holding papers, music, &c., hereinbefore described, and shown in the accompanying illustration.

WILLIAM P. BIGELOW.
